OSCILLATING-CURRENT TRANSFORMER.

1,192,964.

Specification of Letters Patent.

Patented Aug. 1, 1916.

Application filed March 15, 1912. Serial No. 684,033.

To all whom it may concern:

Be it known that I, ROY A. WEAGANT, a citizen of the United States, residing at Brooklyn, in the State of New York, have 5 invented certain new and useful Improvements in Oscillating-Current Transformers, set forth in the following specification.

My invention relates particularly to transformers for oscillating currents such as employed in wireless telegraphy, and its primary objects are to effect changes in degrees of coupling without loss, to improve the coupling in the form of a transformer employing coils set at varying angles with each 10 other, to permit the use of the most appropriate size of wire in a transformer without interfering with the respective adjustments best adapted to different wave length, and to 15 generally improve the construction and operation of such transformers.

The invention is shown as applied to a wireless telegraph circuit in the accompanying drawing, in which—

Figure 1 is a diagram showing the connection of the coils and Fig. 2 is a side elevation of a transformer switch and also showing the primary and secondary coils. Figs. 3 and 4 are respectively an end and a side elevation of the primary coils mounted on an axis for 25 rotation. Fig. 5 is an end view of the primary and secondary coils; and Fig. 6 is a detail sectional view, showing two forms of wire in the secondary coil.

In the form of transformer here used, the 30 primary coil is mounted inside the secondary coil in such a way that the coupling may be varied by turning the primary into positions where the turns will occupy various angles with the plane of the turns in the secondary. 35 In such coils the primary is mounted at an angle of 45 degrees to its supporting shaft and consequently the inside diameter of the secondary must be large enough to allow of the rotation. The result is that when the 40 coils are returned to position of maximum coupling,—that is, the turns of wire in parallel planes—there is a large space all around between the primary and secondary giving a very loose coupling. This space I reduce by 45 using on the primary coil 14 of Figs. 3 and 4, an extra primary 9 and make arrangements for switching it in when using maximum coupling. Another defect in transformers 50 is that on adjustments for shorter wave

lengths, there are many turns of wire not in 55 use and when they idly overhang they have a deleterious effect. I overcome this by a switching device which isolates parts of the coil not being used. Again on wave lengths of above 1200 meters it is very efficient to use 60 flat strip coils so as to obtain a large amount of inductance in a very small space, whereas with shorter wave lengths such coils are not so well suited as other forms of wire. (These differences are especially observable in using 65 the electrolytic detector). I attain the advantage of using the correct kind of wire by making the secondary coil in two parts as shown in Figs. 2 and 6, the dark shaded portion of the coil most closely coupled 70 in the position of maximum coupling, representing the parts wound with the particular kind of wire most efficient for that coupling. In order to obtain these advantages, I arrange the connections of the primary coil as shown in Figs. 1 and 2. From the antenna 7 the lead to the switch 8 is carried through an arm 8^a to various taps on the primaries A or B as will be evident from the diagram. These coils A and B are the 75 coils 9 and 14 in Figs. 3 and 4. The shaft 8 of the switch arm 8^a, is made rigid with the arm 10^a which makes contact with commutator segments 10 and 11, so connecting either one to ground 12. That is, when the arm 8^a 80 is in contact with any of the leads from the larger coil 14, or B in Fig. 1, the arm 10^a is 85 in contact with the commutator segment 11, so that all of the turns of the wire in coil A or 90 9 or in Fig. 4, are isolated. This is the condition for any but the maximum coupling. On the other hand when the primary coil A, B, 95 is so situated that its turns are parallel to those of the secondary coil, and the arm 8^a on any of the leads to section A in Fig. 1, then the arm 10^a is out of contact with the 100 commutator segment 11 and in contact with 10, which isolates all of the wire of the larger coil B. It will be understood that the section 15^a of coil 15 is made of a different form 105 of wire from the rest of the coil, and designed to make the coupling more close.

By this construction I get a closer coupling on shorter wave lengths, eliminating the influences of overhanging turns of the primary and use a wire in the secondary better adapted for short or long waves, according to the position of the transformer.

Other advantages will occur to those familiar with the art.

Having thus described my invention and illustrated its use, I claim the following:

- 5 1. A transformer, comprising a secondary coil and a revolvably mounted two part primary coil mounted eccentrically inside the secondary, and means for isolating either part of the primary coil when desired.
- 10 2. A transformer, comprising angularly adjustable primary coils, a secondary having a winding made of different forms of wire in different parts of the coil more effective respectively according to adjustment in the primary.
- 15 3. An adjustable transformer primary composed of two separate coils each having adjustment tops and means to isolate one of said coils while using any part of the other.
- 20 4. A transformer switching mechanism, comprising a two coil primary, two series of

contacts connected to leads upon said primary coils, a shaft carrying said coils, and a rigidly mounted switch on the same shaft independently connecting the two coils of the 25 primary in the circuit.

5. A transformer, comprising several primary coils mounted to revolve eccentrically inside a surrounding secondary, said primary mounting being attached to switches 30 adapted to cut out one of the primary coils in a certain position with respect to the secondary and the secondary having flat wire in the part most effective in such positions.

In testimony whereof I have hereunto 35 signed my name in the presence of the two subscribed witnesses.

ROY A. WEAGANT.
